(57) **CLAIM**

The ornamental design for a surgical fixation system, substantially as shown and described.

DESCRIPTION

FIG. 1 is a perspective view of one example of a surgical fixation system according to one embodiment of the present invention;

FIG. 2 is a perspective view of a bone plate provided with anti-backout elements forming part of the surgical fixation system of FIG. 1;

FIG. 3 is a top plan view of the bone plate of FIG. 2;

FIG. 4 is a side view of the bone plate of FIG. 2;

FIG. 5 is a partial cross-section view of the bone plate of FIG. 3 without the anti-backout elements, taken along line 1-1 of FIG. 3;

FIG. 6 is a perspective view of an anti-backout element forming part of the surgical fixation system of FIG. 1;

FIG. 7 is a partial cross-section view of the bone plate of FIG. 3 including the anti-backout elements, taken along line 1-1 of FIG. 3;

FIG. 8 is a perspective view of one example of a fixed-angle bone screw forming part of the surgical fixation system of FIG. 1;

FIG. 9 is a perspective view of one example of a variable angle bone screw forming part of the surgical fixation system of FIG. 1;

FIG. 10 is a perspective view of a second example of a variable angle bone screw forming part of the surgical fixation system of FIG. 1;

FIG. 11 is a partial cross-section of the bone screw of FIG. 10;

FIG. 12 is a top view of the surgical fixation system of FIG. 1; and,

FIG. 13 is a partial cross-section view of the surgical fixation system of FIG. 12 taken along line 2-2 of FIG. 12.
